UNITED STATES PATENT OFFICE.

FREDERICK WESTERBECK, OF ST. LOUIS, MISSOURI.

CONTAINER.

979,815.

Specification of Letters Patent. Patented Dec. 27, 1910.

Application filed June 9, 1910. Serial No. 565,933.

To all whom it may concern:

Be it known that I, FREDERICK WESTERBECK, a citizen of the United States of America, residing in the city of St. Louis and State of Missouri, have invented certain new and useful Improvements in Containers, of which the following is a full, clear, and exact description, reference being had to the accompanying drawings, forming part 10 of this specification.

My invention relates to a container designed for use in lieu of sheet metal boxes and sheet metal cans for holding various commodities and from which the commodities 15 are dispensed by merchants. Containers of this description involve considerable expense in their manufacture and they are, therefore, employed by the wholesale merchant for the purpose of transporting commodities to the retail merchant to be used until they have been emptied, after which they are to be returned to the wholesale merchant to be refilled. It is a well known fact 20 that where such containers are made of tin, as they commonly are, they become battered and otherwise injured during transportation and while in the hands of retail merchants, so that the wholesaler is frequently put to 25 the expense of having the containers repaired, and very frequently suffers entire loss of the containers by their being rendered unfit for further service when they are returned from the retail merchant following 30 one or two shipments of merchandise to him. 35

With the foregoing in view, the object of my present invention is the production of a container that will withstand a greater amount of rough usage than the ordinary 40 sheet metal containers and consequently of greater longevity, and which may be produced at approximately the same cost as that involved in the manufacture of sheet metal containers for like service.

Another object of my invention is to provide a container of the kind referred to with a substantial means by which the lid may be held in a closed position through the medium 45 of a seal.

Figure I is a perspective view of my container. Fig. II is a top or plan view of the front portion of the container. Fig. III is a vertical section taken on line III-III, 50 Fig. II. Fig. IV is an enlarged vertical section taken on line IV-IV, Fig. I. Fig. V is an enlarged horizontal section taken on

line V-V, Fig. I. Fig. VI is an enlarged vertical section taken on line VI-VI, Fig. I.

In the accompanying drawings:—A designates the front wall, A' the back wall, B 60 one of the side walls, C the bottom, D a fixed cover section, and E the hinged cover section or lid of my container. The back wall A' is constructed similar to the front wall A.

The front wall A comprises a panel 1 that is of some other material than sheet metal, preferably wood, and channel side strips 2, of sheet metal, a bottom sheet metal channel strip 3, and a top sheet metal channel strip 4, all of said channel strips being 70 fitted to the panel 1 so as to inclose its edges and constitute binding members therefor.

The side walls B comprise panels 5 similar to the panel 1, sheet metal channel side strips 6, a sheet metal channel bottom strip 7, and a sheet metal channel top strip 8, having the same functions as the channel strip 75 of the front wall.

The bottom C of my container comprises 80 a panel 9 of material similar to that of which the panels of the wall of the container are made and edge sheet metal channel strips 10 fitted to said panel. Two or more of the channel strips of the bottom are 85 provided with beads 11 extending downwardly from their bottom portions and which serve as feet to support the container, in order that the greatest area of the bottom of the container may be upheld from 90 contact with a floor or shelf on which the container is placed when in use, this being important in view of the bottom panel being of wood or similar material that is liable to absorb moisture in the event of the container resting upon a damp surface.

The fixed cover section D comprises a panel 12, of material similar to that of which the panels previously referred to are made, a sheet metal lining 15 that is bent upwardly 100 at the side edges and then outwardly, producing side flanges 15' that overlie the side walls of the container and at the rear edge of the panel to produce a top rear flange 14. 13 are angular side strips, each having a 105 wing interposed between the upturned side portion of the lining 15 and the adjacent side edge of the panel 12 and a wing resting on the panel. These strips are connected to the rear flange 14 and the strip 14' by suitable means, such as solder. The lining 15 is bent upwardly at the front edge of the 110

panel 12. Immediately back of this front turned up portion of the lining is an angular strip 14' that connects the side flanges 13 at the top of the section D and one wing 5 of which is interposed between the panel 12 and the front turned up portion of the lining 15.

The hinged cover section or lid E comprises a panel 16 similar to the other panels herein mentioned and a sheet metal lining 17 which is bent upwardly to embrace the rear edge of the panel 16 and then downwardly onto said panel to produce a rear flange 19, the rear flange being secured to side angle strips 18 by suitable means, such as solder. The sheet metal lining extends upwardly at the sides of the panel 16 and then outwardly, producing side flanges 17' that overlie the side walls of the container when the lid is closed. The lining is also extended upwardly at the front edge of the panel 16 and terminates in a flange 20 that extends forwardly from the front edge of the panel so as to overlie the top of the front wall of the container when the lid is closed. This flange terminates in a bead in which is mounted a reinforcing wire 21 that extends transversely of the container and in the flange are apertures 22 and 23 adapted to receive members to be hereinafter more particularly described.

24 is an angular sheet metal strip that connects the side strips 18 of the lid, one wing of said strip 24 for the connection of said side strips being located above the panel 16 and united to the side strips, while the other wing is located between the front edge of the panel and the upturned front portion of the lining 17.

40 The lid E is pivotally connected to the fixed cover section D by a hinge comprising leaves 25 soldered, or otherwise suitably secured, to the lining 17 of the lid and fitted to a pintle rod 26 that is mounted in ears 45 27 formed from the front turned up portion of the lining 15 of the cover section D.

28 designates a sheet metal body lining for the container that is seated within the body comprising its several walls and bottom, this body lining being extended to the tops of the container walls and being then bent downwardly upon itself and then inwardly, as seen most clearly in Fig. IV, to provide a seat 29 for the lid E when it is closed, such seat being continued beneath the fixed cover section 12 to assist in its support.

In the manufacture of my container, the various walls, bottom and top members are constructed separately so that each includes a panel of material, such as wood, which is less susceptible of injury than the thin sheet metal, owing to its greater thickness, and also includes the sheet metal binding members incasing the edges of these panels. The

body of the container is then produced by arranging the walls in their proper relation upon the bottom and all of these parts are connected by joining the sheet metal binding strips, solder being preferably used 70 for the connection of the strips to each other. The body of the container is completed by the connection of the fixed cover section to the rear and side walls in a manner similar to that in which the walls are united 75 to each other.

Having now described the construction of my container in general, I will proceed with the description of the devices provided for sealing the lid of the container in a closed 80 position. F are seal receiving members, preferably made of wire, and each comprising a body portion 30 that extends longitudinally within the top channel strip 4 of the front wall of the container from which 85 the wire is bent upwardly to extend through an aperture 4' in the top of the strip 4 and through the aperture 22 in the front flange of the lid E that registers with the aperture 4 when the lid is closed. A loop 31 is produced from the wire and this loop overlies the central portion of the front flange of the lid so that it opposes the companion loop of the other seal receiving member. From the loop 31 the wire extends downwardly through the apertures 22 and 4' and then beneath the central portions of the strip 4 and the lid flange in the form of an arm 32 that serves to limit the upward movement of the loop 31 above the hinged cover section or lid. The end of the body 30 of each seal receiving member F extends upwardly through an aperture 4^a in the top strip of the front wall and through the aperture 23 in the lid flange that registers with said 105 aperture 4^a, and this end is bent so as to overlie the flange of the lid, thereby producing an arm 33 that faces the rear end of the loop 31 and acts to hold the hinged cover section or lid from upward movement when 110 it is closed, and the seal receiving members are in the positions shown in the drawings. The apertures 22, 23, 4' and 4^a are elongated and, therefore, the seal receiving members may be at one time in a position to permit 115 of the loops 31 and arms 33 being at one time in position in the apertures in the front flange of the lid to provide for the lid being opened, and when the seal receiving members are shifted into lid fastening position; that is to say, the position in which they are shown in the drawings, a seal X may be applied to them by passing it through the loops of the members, thereby 120 preventing unwarranted opening of the 125 container without breaking the seal and furnishing a tell-tale of the fact that the container has been opened.

I claim:

1. A container comprising a body, a lid 130

having a fixed cover section provided with a lining bent upwardly at the sides and outwardly, producing flanges overlying the side walls of the body, and also bent upwardly at 5 the front edge and provided with ears, and a hinged cover section provided with a lining bent upwardly at the sides and outwardly, producing flanges overlying the side walls of the body, and also bent upwardly at 10 at the front edge, and provided with a flange overlying the front wall, the leaves between the cover sections, and a pintle rod connecting the ears and the leaves.

2. A container comprising a body having 15 a lining extended to the top of the walls, bent downwardly upon itself and then inwardly to provide a seat for a lid.

3. A container, comprising a body having a front wall provided with a top member 20 containing elongated apertures, a lid hinged to said body and having a front flange provided with elongated apertures for registration with the apertures in the top member of said front wall, and seal receiving members 25 slidably arranged in the top member of said front wall and extending through the apertures therein, the seal receiving members being arranged for passage through the apertures in the flange of said lid to be shifted 30 over said flange.

4. A container, comprising a body having a front wall provided with a top member

containing elongated apertures, a lid hinged to said body and having a front flange provided with elongated apertures for registration with the apertures in the top member of said front wall, and seal receiving members slidably arranged in the top member of said front wall and extending through the apertures therein, the seal receiving members being arranged for passage through the 40 apertures in the flange of said lid to be shifted over said flange, and being provided with loops at their facing ends.

5. A container, comprising a body having 45 a front wall provided with a top member containing elongated apertures, a lid hinged to said body and having a front flange provided with elongated apertures for registration with the apertures in the top member 50 of said front wall, and seal receiving members slidably arranged in the top member of said front wall and extending through the apertures therein, the seal receiving members being arranged for passage through the 55 apertures in the flange of said lid to be shifted over said flange, and being provided with loops at their inner and facing ends and upturned arms at their outer ends.

FREDERICK WESTERBECK.

In the presence of—

E. B. LINN,
A. J. McCauley.
